UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

COMBINED DOORSTOP AND KEEPER PLATE.

Application filed March 7, 1922. Serial No. 541,640.

To all whom it may concern:

Be it known that I, ELLIS J. G. PHILLIPS, a citizen of the United States, and a resident of Aurora, in the county of Kane and State 5 of Illinois, have invented certain new and useful Improvements in Combined Doorstops and Keeper Plates, of which the following is a specification, reference being had to the accompanying drawings.

10 It is common to provide certain hinged doors that are used for closing large doorways with a locking mechanism that comprises two bolts extending, respectively, upwardly and downwardly from a common 15 actuating member, one of said bolts being adapted to be projected into a keeper carried by the overhead beam of the doorway frame and the other bolt into a keeper set into the floor. It is usual to so construct the frame 20 of the doorway that a positive stop is provided for the upper edge portion of the face of the door to strike against when the door is brought to its fully closed position, and the striking of that upper part of the door 25 against such fixed stop ensures the upper locking bolt being brought directly opposite the socket or keeper that is provided to receive it. There is ordinarily no stop provided for the lower edge portion of the door 30 to strike against and it is, therefore, frequently the case that more or less difficulty is experienced in bringing the lower locking bolt into the required alinement with the floor socket or keeper, such difficulty being 35 frequently increased because of the door having become somewhat warped.

It is an object of my invention to provide a device for attachment to the floor of a building which will serve both as a stop for 40 the lower edge portion of a door and as a keeper for the lower locking bolt that the door is provided with. Inasmuch as the doors vary in thickness it is evident that if the distance between the stop that the face 45 of the door comes in contact with and the socket that such bolt enters was not capable of being varied such combined stop and keeper could only be used in connection with one thickness of door. To avoid the objection 50 of a dealer having to carry in stock a quantity of the said devices for doors of

different thicknesses is another object of the invention, and broadly stated, I accomplish this by making the stop and keeper members relatively movable,—in the construction 55 shown the keeper being in the form of an apertured plate slidably mounted upon a base that has an upturned end portion that constitutes the door stop, such plate being adapted to be secured to the base in any of 60 its adjusted positions. A further object of the invention is to render such adjustable keeper-plate adaptable for use in connection with doors of the maximum as well as the minimum standard thicknesses without 65 being obliged to rely upon moving such plate longitudinally of the base that it rests upon, and this I accomplish by making the opening in such plate, and into which the said locking bolt projects, at unequal distances 70 from its ends, whereby by turning the plate end for end the bolt-receiving opening therein can be positioned for receiving the locking bolt on any standard thickness of door, whereas if such opening were midway of 75 the ends of the plate the movement of the keeper plate longitudinally of the base would be the only way to effect the desired adjustment. Furthermore, in view of the quarter-inch differences in thickness that 80 generally prevails with respect to such doors it would not be feasible to properly arrange the openings in the base that receive the bolts that attach the keeper to the base if successive adjustments were made merely by 85 moving the keeper along on the base. By my construction, however, each of such openings for the securing bolts is adapted for use when the device is employed in connection with either one of two thicknesses of doors. 90

In the drawings,—

Fig. 1 is a perspective view of portions of two hinged doors, to one of which is applied a locking mechanism comprising an upper and a lower bolt adapted to be simultaneously projected or retracted, and showing my improved combined keeper and stop in position;

Fig. 2 is a plan view of my improved device with the adjustable keeper member 100 thereof secured in position for use in connection with a door of minimum thickness,

and showing by dotted lines its position when reversed end for end to accommodate a door of the next standard thickness;

Fig. 3 is a vertical section taken at line 5 3—3 of Fig. 2 and showing a portion of a door and the lower locking bolt carried thereby, the door being shown as bearing against the stop and the bolt in engagement with its keeper to lock the door in place;

10 Fig. 4 is a cross-section taken at line 4—4 of Fig. 2;

Fig. 5 is a perspective view of the base member of the combined keeper and stop; and

15 Fig. 6 is a perspective view of the sliding apertured plate that is adapted to be adjustably secured to the base member and when so secured thereon form a keeper for the door-bolt.

20 Referring to the several figures of the drawing,—A—B indicate two ordinary hinged doors adapted together to close a large doorway. To the inner face of one of the doors—A in the construction illustrated—is attached a locking mechanism near the free edge of the door, such mechanism comprising upper and lower bolts C and D, respectively, each of said bolts being secured at its inner end to a link, which 25 links are indicated by E and F, respectively. The inner ends of the two links are pivotally connected to a rotatable plate enclosed in a casing G which is turned by means of a handle H connected with the 30 said rotatable plate by means of a shaft that projects through the casing. Each bolt passes loosely through a guide near the upper and lower parts of the door, which guides are indicated respectively by I and J.

40 Locking mechanisms of this general type are common and well understood and need no further description. Each of the bolts when in locking position projects into a keeper, which keepers are respectively connected with the upper cross-bar of the doorway frame and the floor of the building—such a cross-bar being here indicated by K and the floor by L.

45 My invention has particularly to do with the means for retaining the lower one of such bolts, and, as here shown, such means comprises two principal elements, to-wit, a base and an apertured plate adjustably secured upon such base. The base member is indicated generally by 10, and as here shown it is of oblong shape and provided at one end with a heavy lip 11 that rises above the face of the base sufficiently to serve as a stop for the door. The base 50 as a whole is adapted to be set into a correspondingly-shaped recess in the floor, such recess being indicated by M, and of a depth to bring the face of the base substantially flush with the surface of the floor.

60 65 As shown, the base is provided with a down-

wardly-extending marginal flange 12, the edge of which rests on the bottom of the recess M, thus leaving a space between the bottom of such recess and the central or body portion of the base, thereby providing sufficient room to receive certain fastening devices that attach to this base the adjustable keeper, as hereinafter described (see Fig. 4).

The top wall of this base is formed with a large oblong opening 13 therethrough, and, for convenience, I shall refer to that portion of the top wall of the base adjacent to the upstanding lip 11 as a cross-bar and designate it by the numeral 14, and shall refer to the portion of such wall at the other end of the base as a cross-bar and designate it by the numeral 15. 16 and 17 indicate, respectively, two inwardly-extending ledges at opposite sides of the opening 13, each of said ledges being slightly below the plane of the upper faces of the end cross-bars 14 and 15, as clearly shown in Fig. 5. The edge of that portion of the ledge 16 that lies adjacent to the cross-bar 14 has formed in it semi-circular notches spaced at regular intervals apart and indicated respectively by 16^a, 16^b and 16^c, and in the edge of that portion of the ledge 17 adjacent to the end cross-bar 15 is a similar series of spaced-apart notches which are indicated, respectively, by 17^a, 17^b and 17^c. 18 indicates a plate that is rabbed at opposite sides in its under face as indicated at 19 to adapt it to rest upon the ledges 16 and 17, and have its upper face substantially flush with the upper faces of the cross-bars 14 and 15 of the base member. This plate 18 has formed therethrough an opening 20 which is considerably nearer one end of the plate than the other end, and, for convenience of description, I shall refer to the narrower portion at one end of this plate as the end 21, and to the wider end portion as the end 22, and so indicate these parts on the drawing. Adjacent to diagonally-opposite corners the plate 18 is provided with bolt holes 23, 24, respectively, and when the plate is in position on the ledges 16 and 17 with its narrower end portion 21 opposite the cross-bar 14 of the base the bolt hole 23 is adapted to register with one of the notches in the ledge 16 and at the same time the other bolt hole will register with one of the notches in the other ledge. The plate is adapted to be secured to the base by means of two screw bolts 25 and nuts 26 (see Fig. 4).

115 It is common practice to make doors of the character with which my improvements will be used of standard thicknesses, such thicknesses being in inches 1 $\frac{3}{4}$, 2, 2 $\frac{1}{4}$, 2 $\frac{1}{2}$, 2 $\frac{3}{4}$, and 3, and according to the positioning of the keeper plate 18 on the base 10 such plate 120 will be adapted to have received in its open- 125 130

ing 20 the end of a bolt, such as D, carried by a door of any such thickness. As shown, the base 10 is screwed firmly to the floor at the proper place to bring the upstanding lip 11 in position to have the lower part of the door A abut against it, such fastening of the base in place being, in the construction shown, by screws 27 that pass through holes 28 near opposite ends of the base. Before the base is attached in place, however, the keeper plate is to be adjusted with reference thereto and bolted in position, and its position on the ledges 16 and 17 will be determined by the thickness of the door. If the door is one of minimum thickness the end portion 21 of the keeper plate will abut against the cross-bar 14 and in that position the bolt hole 23 will register with the notch 16^a in the ledge 16 and the bolt hole 24 will register with the notch 17^a in the ledge 17. If, however, the door be of the next standard thickness, which is here assumed to be two inches, the position of the keeper plate will be reversed end for end so that its end portion 22 lies against the cross-bar 14 of the base, and when in that position its bolt hole 23 will register with the notch 17^a and its bolt hole 24 will register with the notch 16^a and by reason of such reversal of the plate the opening 20 therein will be carried just enough farther away from the cross-bar 14 to properly position such hole to receive the locking bolt carried by the two inch door. For the next standard thickness of door, viz, one of 2 $\frac{1}{4}$ inches, the keeper plate will be again positioned with its narrower end portion 21 adjacent to the cross-bar 14 of the base but sufficiently removed therefrom to bring its bolt holes 23 and 24 in register with the notches 16^b and 17^b, respectively. For the next standard thickness of door, namely, one of 2 $\frac{1}{2}$ inches, the keeper plate would be reversed end for end but its bolt holes would still register with the notches 16^b and 17^b, but by reason of the greater width of the end portion 22 of the plate its bolt-receiving hole 20 will be carried just enough farther away from the cross-bar member 14 to permit it to be engaged by the bolt on this thicker door. The same manner of adjusting the keeper would be followed in adapting it for receiving the locking bolt carried by doors of the next two standard sizes—that is for the 2 $\frac{3}{4}$ inch thickness of door the keeper plate would have its narrower end portion 21 toward the cross-bar 14 of the base and for the 3 inch thickness of door would have its wider end portion 22 so located, but in both such adjustments the bolt holes of the keeper plate would aline with the notches 16^c and 17^c, respectively.

By my invention I provide not only a very effective and securely affixed stop for a door to abut against in its closed position, but I provide also in connection therewith a keeper

plate that can be very readily and easily firmly secured to the base plate that carries the stop, and which can be so adjusted along the base as to adapt it for use in connection with a locking bolt carried by doors of different standard thicknesses. Such an adjustability is a matter of great convenience to dealers in and users of builders' hardware, for with the dealer it obviates the necessity of carrying in stock a comparatively large quantity of devices, and with builders it obviates the necessity of having to specify with exactness the number of such articles as may be required in connection with a job having a large number of such doors, which doors in different situations on the same job may be of different thicknesses. It is also of very considerable advantage to so construct the keeper plate that the portion at one side of the bolt-receiving opening is of a different width from that at the other side, because the base can be made somewhat shorter than if the keeper plate were merely slid along a quarter of an inch each time an adjustment for a next greater thickness of door must be made, and, furthermore, such an adjustment of a quarter of an inch at a time would be so small as to preclude the proper spacing apart of notches for the reception of the securing bolts that hold the plate to the base. Of course, it is to be understood that the widths of the portions 21 and 22 will be properly related to each other so that a reversal of the keeper plate end for end will secure the desired quarter-inch shifting of the bolt receiving hole 20. This will be secured by providing that the holes 23 and 24 will be so related in position to the large opening 20 that the difference between the distance from a line drawn across the plate 18 through the center of such opening 20 to a parallel line drawn through the center of the hole 23 must vary from the distance between the center of such opening 20 and a corresponding line drawn through the center of the hole 24 to the same extent, or in the same amount, as the variation of the steps of the adjustments that are to be provided for.

What I claim as my invention and desire to secure by Letters Patent, is—

1. The combination with a door and a bolt arranged longitudinally of the door and slidingly secured against a face thereof, of a combined stop and keeper comprising a base adapted to be secured in place beneath the lower edge of the door and extending beyond both faces of the door when the door is closed, said base having an abutment at one end for one face of the door to strike against and having an opening in that portion that extends beyond the other face of the door to receive said bolt.

2. The combination with a door and a bolt arranged longitudinally of the door and

slidingly secured against a face thereof, of a combined stop and keeper comprising a base adapted to be secured in place beneath the lower edge of the door and extending beyond both faces of the door when the door is closed, said base having an abutment at one end for one face of the door to strike against, and a member mounted on said base adapted to receive and hold said bolt mounted on the opposite face of the door, said abutment and member being relatively movable toward and from each other.

3. The combination with a door and a bolt arranged longitudinally of the door and slidingly secured against a face thereof, of a combined stop and keeper comprising a base adapted to be secured in place beneath the lower edge of the door and extending beyond both faces of the door when the door is closed, said base having an abutment at one end for one face of the door to strike against, and a member located between the opposite end of the base and the other face of the door adapted to engage and hold the said bolt, said abutment and member being relatively adjustable toward and from each other.

4. The combination with a door and a bolt arranged longitudinally of the door and slidingly secured against a face thereof, of a combined stop and keeper comprising a base adapted to be secured in place beneath the lower edge of the door and extending beyond both faces of the door when the door is closed, said base having an abutment at one end for one face of the door to strike against, a bolt-holding keeper adjustable longitudinally of the base and located between the opposite end of the base and the other face of the door, and means for holding said keeper in its different adjusted positions.

5. The combination with a door and a bolt arranged longitudinally of the door and slidingly secured against a face thereof, of a combined stop and keeper comprising a base adapted to be secured in place beneath the lower edge of the door and extending beyond both faces of the door when the door is closed, said base having an abutment at one end for one face of the door to strike against, an apertured bolt-holding keeper adjustable longitudinally of the base and located between the opposite end of the base and the other face of the door, and means for holding said keeper in its different adjusted positions.

6. The combination with a door and a bolt arranged longitudinally of the door and slidingly secured against a face thereof, of a combined stop and keeper comprising a base adapted to be secured in place beneath the lower edge of the door and extending beyond both faces of the door when the door is closed, said base having an abutment at one

end for one face of the door to strike against and having a comparatively large opening in that portion of its upper wall that lies beyond the other face of the door, an apertured keeper-plate mounted over said opening, means carried by the base for supporting the side marginal portions of said plate, and means for securing said plate to said base in different adjusted positions.

7. The combination with a door and upper and lower bolts arranged longitudinally of the door and slidingly secured against a face thereof, said bolts being adapted to be projected beyond the upper and lower edges of the door, respectively, of a fixed keeper to receive the said upper bolt, and a combined stop and keeper comprising a base adapted to be secured in place beneath the lower edge of the door when the door is closed and projecting beyond both faces of the door, one of such projecting end portions being provided with an abutment for one face of the door to strike against and the portion projecting beyond the other face of the door having adjustably mounted thereon an apertured keeper plate for said lower bolt, and means for securing said plate to said base in its different adjusted positions.

8. An article of the class described, comprising in combination a base having a comparatively large opening in its upper wall, and having at each side of said opening a ledge located below the plane of the upper face of the base, each of said ledges having a plurality of notches in its edge, a keeper slidingly mounted on said ledges, and bolts passing through the keeper at opposite sides thereof and adapted to engage said notches for holding the keeper in a plurality of adjusted positions.

9. An article of the class described, comprising in combination a base having an abutment at one end for a door to strike against, said base having a comparatively large opening in its upper wall and having at each side of said opening a ledge, one of said ledges having adjacent one end of said opening a plurality of spaced-apart notches in its edge and the other ledge having a plurality of similarly-spaced notches in its edge adjacent the other end of said opening, a bolt-receiving keeper slidingly mounted on said ledges, and bolts passing through the keeper at opposite sides and near opposite ends thereof and adapted to engage respectively with the notches in the ledges for holding the keeper in a plurality of adjusted positions.

10. An article of the class described, comprising in combination a base having at one end an abutment for a door to strike against, a keeper resting upon said base and having a hole for receiving a door-bolt, said hole being nearer to one end of the keeper than it is to the other end thereof, whereby the keeper

by being reversed end for end will be adapted to receive bolts carried by doors of different thicknesses, and means for securing the keeper to the base in either of such positions.

11. An article of the class described, comprising in combination a base having an abutment at one end for a door to strike against, a door-bolt keeper mounted on said base and adjustable longitudinally thereof, said keeper having a bolt-receiving hole that is nearer one end of the keeper than it is to the other end thereof to adapt it for use with doors of different thicknesses by reversing it 10 end for end, and means for securing the keeper to the base in any of a plurality of longitudinally-adjusted positions and irrespective of which of its ends is nearer the abutment.
12. An article of the class described, comprising in combination a base having an abutment at one end for a door to strike against, a door-bolt keeper mounted on said base and adjustable longitudinally thereof, 20 said keeper having a bolt-receiving hole that is nearer one end of the keeper than it is to the other end thereof to adapt it for use with doors of different thicknesses by reversing it end for end, and means carried by the keeper

for securing it to the base, said means engaging the base at the same place for each two successive adjustments that are made by said end to end reversal of the keeper.

13. An article of the class described, comprising in combination a base having an abutment at one end for a door to strike against, said base having a comparatively large opening in its upper wall and having at each side of said opening a ledge, one of 30 said ledges having adjacent one end of said opening a plurality of spaced-apart notches in its edge and the other ledge having a plurality of similarly-spaced notches in its edge adjacent the other end of said opening, a bolt-receiving keeper slidingly mounted on 40 said ledges and having a hole for receiving a door-locking bolt, said hole being nearer to one end of the keeper than it is to the other end to adapt it to be brought into alignment with bolts on doors of different 50 thicknesses by reversing the keeper end for end, and bolts passing through the keeper at opposite sides and near opposite ends thereof for engaging respectively with the notches in the two ledges for holding the keeper in 55 a plurality of adjusted positions.

ELLIS J. G. PHILLIPS.
